CLAIM

The ornamental design for an alarm clock projection light, as shown and described.

DESCRIPTION

FIG. 1 is a first perspective view of an alarm clock projection light showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of the selected portion 9 in FIG. 2.

The evenly-spaced broken lines shown in the drawings depict portions of the alarm clock projection light that form no part of the claimed design. In FIGS. 2 and 9, the dash-dot-dash broken lines represent a sectional designation that forms no part thereof.
